CARBON PAPER FOR BILLING MACHINES
AND THE LIKE

Frank G. Poczatek, Chicago, Ill.

Application July 21, 1952, Serial No. 300,104

3 Claims. (Cl. 282—19)

1

This invention relates to carbon paper for use on billing machines and similar office machines, where such paper is manifolded with strip-form or fan-fold stationery. More particularly the invention relates to carbon paper of the long, zigzag-folded type, with novel holder means for the same.

Heretofore a number of constructions of carbon sheets and holders for the same have been devised and used, as shown and described, for instance in the patents of L. A. Petit 2,236,155; J. H. McAlvin 2,292,343; W. J. Feitl 2,363,661 and J. A. Heckman 2,600,535 and the art cited therein.

General objects and desirable properties of carbon paper of the present type are known from the prior art mentioned. For instance this carbon paper should allow use on different kinds of typewriters and typewriter attachments and similar machines. Attachment and detachment and other required manipulations should be as simple as possible. The fullest possible use should be made of each carbon sheet. Irregularity of copying effect should be avoided or held to a minimum. Each carbon sheet should safely and strongly be held in a flat, folded condition, except when and so far as it is positively unfolded by the operator. Such unfolding should be possible for the operator without substantial inconvenience or loss of time. For efficiency and convenience in shipment and storage, the folded carbon sheets should form thin, flat units and should be substantially free from irregularities in thickness which cause irregular wear of carbon material. Finally each unit should be as light as possible since every ounce of extra weight makes the machine operation slower and noisier.

In several of these respects the new unit is improved over those known to the prior art. It can be attached to practically all known machines with the greatest of ease and without need of special attachment means. It can be manipulated with particular speed and safety, once that it has been attached to a machine. Shipment and storage as well as normal use are facilitated. The carbon sheet can be used up to the last inch of the available supply. Irregularities of copying effect are practically avoided.

These improvements are obtained by a construction which employs only three parts of the utmost simplicity: a flat, singly folded carbon holder of strong paper or the like; a long, zigzag-folded carbon sheet within the holder, with front and back folds equally spaced from one

another and uniformly staggered; and a few small adhesive pads at the front edge of the carbon holder, extending below the front folds of the carbon sheet and firmly but releasably securing such front folds to the carbon holder. The manufacture as well as the use of the unit is simplified by this construction.

The advantages and more detailed features of the new unit and of its parts will be understood more clearly upon a perusal of the detailed description of a preferred embodiment which follows, with reference to the drawing, wherein

Figure 1 is a perspective view of the new article in the form as delivered to the user;

Figure 2 is a perspective diagrammatic view of the new article in one phase of actual use;

Figure 3 is a partial view generally similar to Figure 2, showing a different phase of the use of the article;

Figure 4 is a greatly enlarged section along lines 4—4 in Figure 3, and

Figure 5 is a diagrammatic, exploded cross section through the article, in a view generally similar to that of Figure 4.

The carbon holder 10 as shown has a bottom sheet 10B and a top sheet or top flap 10T; these bottom and top parts 10B, 10T being connected together at a fold line 10L which in actual use will be at the back end of the unit. The top and bottom parts are substantially rectangular and uniform in shape and area, thereby forming a very simple envelope for the carbon sheet 11. This envelope is about as wide as is the manifoldded form or stationery to be typed upon, and it may be as long as such stationery, or may cover only a fraction of the length of such stationery.

The carbon sheet 11 forms a rectangular unit, about as wide as the carbon holder 10 but many times longer in order to minimize the necessity for attaching and detaching operations. A suitable transfer material such as carbon ink forms a coating 11C of one side of the carbon sheet. A plurality of zigzag-folded sections are formed in the carbon sheet; each section comprising a bottom part 11B and a top part 11T. The first section consists of bottom part 11B1 and top part 11T1; the second of parts 11B2 and 11T2, etc. These successive parts and sections are substantially uniform with one another in form and size, except that the first and lowermost bottom part 11B1 preferably is shorter than the other parts 11B2, 11B3, etc., and forms a mere strip, for attachment of the holder 10. Adjacent the front of this holder, a front fold 11F is formed between every pair of bottom and top parts 11B, 11T.

3

The folds are staggered, so that successive front folds $\text{II}F_1$, $\text{II}F_2$, etc., come progressively closer to the front edge of the carbon holder, as shown most clearly in Figure 4; thereby exposing a narrow strip of each section to the carbon holder bottom sheet for purposes of attachment. This spacing between pairs of front folds $\text{II}F_1$, $\text{II}F_2$, etc., is substantially uniform. It amounts, desirably, to a distance such as one-eighth of an inch. The spacing between these front folds $\text{II}F$ 10 and the back folds $\text{II}L$ in the carbon sheet—the latter being adjacent the line $\text{II}L$ —is also uniform. Desirably it often amounts to a distance such as five or six or seven inches, subject to considerable variation depending upon the type of 15 the stationery for which the carbon sheet is intended. Due to the staggering of the front folds $\text{II}F$ and the uniformity of the intermediate section parts $\text{II}B$, $\text{II}T$, the back folds $\text{II}L$ will usually be staggered in a manner similar to the front 20 folds; however, they are not attached to the carbon holder.

The adhesive pads $\text{I}2$ below the front folds $\text{II}F$ are desirably formed by small strips of paper, 25 fabric or the like. Their lower sides are coated with glue $\text{I}2G$ or the like for permanent attachment to the top of the carbon holder bottom $\text{I}0B$. Their upper sides are coated with dry sealing adhesive $\text{I}2A$ in order to releasably secure the front folds $\text{II}F$ to the front part of the carbon 30 holder bottom sheet $\text{II}B$. Preferably the width of every pad or strip $\text{I}2$ is only a minor fraction of the width of the carbon holder, in order to minimize the time required for release and unfolding and the resulting effects upon the copying 35 characteristics of the carbon sheet. The length of every pad or strip $\text{I}2$ slightly exceeds the distance from adjacent the front to the lowermost front fold $\text{II}F$. More particularly, as shown in Figure 4, each pad $\text{I}2$ extends from a location between the first front fold $\text{II}F_1$ and the back folds $\text{II}L$ forward to a location directly below the second before last front fold $\text{II}F_X$ and behind the very last front fold $\text{II}F_Y$; thereby allowing immediate use of the uppermost section $\text{II}T$, $\text{II}B$ 40 without a releasing operation.

Each carbon holder $\text{I}0$ is secured to the form carrier or attachment of the typewriter or other business machine. This can be done by suitable, well-known support arms, clips or the like, inserted in the space between the back folds $\text{II}L$ of the carbon sheet and the back fold $\text{I}0L$ of the carbon holder. The attachment bar or equivalent device is inserted in known manner between the top and bottom sheets $\text{I}0P$, $\text{I}0B$ of the carbon holder, behind the back folds $\text{II}L$ of the carbon sheets. In order to facilitate such insertion said space between the folds $\text{II}L$ and $\text{I}0L$ is preferably made long enough for the usual attachment of bars, by suitably locating the attachment pads $\text{I}2$ adjacent the opposite edge of the carbon holder.

For actual operation, there is usually a plurality of the carbon units supported on the form carrier; said units being disposed above one another, manifolded with one sheet of paper or the like below each carbon unit. (In Figure 2 the sheets of paper have been omitted and the vertical spacing between the carbon units has been exaggerated in the interest of a clearer diagrammatic representation.)

At the start of operation, the top section of each carbon sheet is unfolded from within the holder $\text{I}0$; the front portions of the stationery to be typed upon and the front top portions of the interleaved carbon sheets are lined up at their

4

front edges; and these front edges are then inserted below the platen of the machine, so that they are curved upward as shown in Figure 2. Such insertion is usually accomplished with the platen in raised position. The operator then lowers the platen to its normal typing position and begins actual type work.

As the platen moves from right to left, the form carrier with the system of carbon units and interleaved stationery portions thereon moves along from right to left. Likewise as the platen is turned to change from one line to another the system of carbon units and interleaved stationery portions moves with the platen. Forward movement of this entire system is effected by forward turning of the platen. Backward movement of the system is effected upon backward turning of the platen, by mechanism which is conventionally incorporated in the form carrier. Such mechanism, by means of the attachment clips, holds the carbon holders $\text{I}0$ and thereby the forwardly extending section of the carbon sheet II under a slight backward tension, away from the platen.

As a result of such backward tension, the dry-seal joint between the top $\text{I}2A$ of each adhesive pad $\text{I}2$ and the uppermost front fold $\text{II}F$ secured thereto is subject to some little stress in a direction parallel with the plane of the carbon holder paper. Some such stress prevails continuously; and a particularly strong force is applied whenever the platen is turned. I found that a sufficiently high resistance to a so directed force or stress, to prevent irregular, misdirected shifting of the carbon holders between the stationery sheets, is provided by any of the well-known permanently tacky compounds for dry sealing on paper and the like. Such a compound may contain a rubber or latex base with suitable admixtures, as is well known from the art of adhesives used in mailing envelopes and the like. In the present application the dry sealing compound on top of the pad $\text{I}2$ engages the underside of the carbon sheet II (normally not coated with carbon ink but sometimes coated with wax $\text{I}2W$ or the like) and holds the same to the pad and thereby to the carbon holder bottom $\text{I}0B$ against the forces referred to.

Release of this holding effect is possible, by operations to be described presently.

When a first invoice or other stationery item has been typed the platen is raised again to allow forward pulling of the entire system of sheets; then the operator holds the system of stationery sheets in position while allowing the system of carbons to slide back under the backward tension applied thereto, by a sufficient distance for work on the next invoice; then the first invoice is torn off; the platen is lowered and turned forward or backward a sufficient distance; and the next invoice is typed in the same manner as the first. When this has been repeated a number of times, the portion of the carbon sheet used in this work is sufficiently worn to be discarded. At such times, when an invoice has been completed, the front part of the carbon as well as the stationery is separated from the remainder, in known manner, instead of sliding the carbon back as mentioned before. Depending on the relative length of the unfolded carbon and the stationery used it may or may not be necessary at this time to unfold an additional length of carbon from its folded condition between the top and bottom flaps of the holder $\text{I}0$. If and when such unfolding is necessary it can be ef-

fected in the manner diagrammatically shown in Figure 3.

Here it is assumed that the foregoing used-up portion of the carbon sheet has been separated directly at the front edge of the carbon holder. The operator now uses two fingers to lift up one corner of the carbon holder top 10T and of the directly underlying, uppermost carbon sheet portion 11B, as shown at the right front edge in Figure 3. The said carbon portion 11B adheres to the top 12A of the adhesive pad 12 at the right corner, but such adhesion can be overcome by lifting up the aforementioned parts 10T and 11B. In other words, the dry sealing materials mentioned have less resistance to the peeling off incident to such lifting up than to the aforementioned stresses parallel to the plane of the paper.

As the seal between each pad 12 and the carbon sheet 11 is broken a small amount of wax from a waxed reverse side 11W of the carbon sheet will remain on the adhesive coating 12A of the pad, partly or fully preventing any repeat sealing. This is unobjectionable in the present application. In fact it is desirable since this feature prevents subsequent adhesion between the spent portion of the pad and the newly unfolded carbon sheet portion which is next brought into contact therewith. If there were such adhesion with a spent portion of the pad and if the adhesion were strong, it would become necessary to apply increasing effort for the release of successive carbon sections. The arrangement as described on the other hand involves uniform releasing operations at each front fold 11F. Each adhesive pad 12 in effect provides a series of short and narrow sealing areas, transversely of the pad, which are spent by releasing operations, one after the other and which thereafter will not apply any strong adhesive action upon the waxed reverse side portions of the carbon sheet successively contacted therewith.

This non-repeat sealing has additional advantages, at least in some instances where relatively delicate carbon coating must be used on the carbon sheet. In such cases the removal of wax 11W from any extended portions of the reverse side would undesirably affect the copying characteristics of equally extended areas of the carbon ink coating. On the other hand, the existence of two or three short and narrow areas so affected is harmless. The areas, as mentioned above, need not be any wider than about one-eighth of an inch and they can be kept at the top edge or bottom edge of the form to be typed upon where they do not interfere with any actual type work.

Accordingly it will be seen that it is most desirable for present purposes to use a somewhat special construction of the adhesive pad and also a somewhat special construction of the carbon sheet. The adhesive pad, dimensioned and arranged in the manner as described, is best formed by a rather thin strip of paper or the like, with ordinary, usually wet sealing and non-tacky adhesive 12G at the bottom side and the aforementioned tacky and dry sealing adhesive 12A on the top side; the dry sealing being suitably selected for cooperation with the reverse side 11W of the carbon sheet. It is also possible to apply such dry sealing compound to the top of the carbon holder bottom 10B direct, at suitable locations; however better results can often be obtained by the separate, double coated pads or strips which I have described. The reason is that different dry sealing compounds may best be provided for

different types of carbon sheet; reverse sides and irrespective of the different dimensions, imprints and other features of the carbon holders and carbon sheets. Moreover, dry seal compounds usable in engagement with the reverse side of a carbon sheet will usually tend to adhere also to the paper of a carbon holder. For this reason they would complicate the manufacture and storage of carbon holders. On the other hand, no problem whatsoever is presented when the double sealed pads are simply cut off from a long strip and installed in the carbon holders practically at the same time with the prefolded carbon sheets.

Instead of tearing off the carbon paper directly at the front edge of the carbon holder as shown in Figure 4 the operator can tear it off some suitable distance in front of said edge. In that event a transverse strip of the last used top portion 11T will still adhere to the front fold 11F. The advantage is that the operator will not have to touch the carbon coated side 11C of the carbon sheet with his fingers during any phase of the manipulation; not even when pulling out the released carbon for interleaving between the stationery.

The outer side of the top flap 10T of the carbon holder will often be imprinted with the manufacturer's name and address or with advertising matter or the like. Such imprints are not shown in the drawing. However as shown in the drawing said top flap may be additionally imprinted with markers or indicia 12P substantially coextensive with and overlying the seal pad or seal spot 12 on the holder bottom 10B. Such markers may be desirable in some instances in connection with the releasing operation. When any additional supply of carbon paper is needed the operator must pull the forwardly extended sectional portion of the carbon paper upward as mentioned above, and the operation is usually facilitated if he simultaneously presses down with a fingertip on the underlying portion of the carbon holder bottom. While the carbon holder bottom itself is substantially obscured by overlying carbon sheet sections, and in any lower, manifoldded unit also by overlying stationery, the markers 12P on the uppermost carbon paper unit will show very clearly the successive points to be held down for the unfolding of each carbon sheet.

The fact that these markers, and the seal strips themselves are located at the front edge of the unit provides a further advantage in simplifying the carbon release and supply operation. The operator can perform the entire operation from the normal typing position, with greater ease and convenience than if the attachment were effected along the side or back edge of the unit. Moreover the front attachment described has the further advantage that practically no part of the carbon sheet is wasted; everything but the narrow bottom section 11B1 can be used up for actual type work.

It will be understood by persons skilled in the art that various additions and modifications are possible. For instance the unit may contain a protective paper sheet in addition to the carbon sheet shown and described, in which event the carbon sheet may be carbon coated on both sides. The sheet 11 may also be coated with transfer materials other than carbon ink; and various other modifications can be applied.

I claim:

1. A transfer unit for billing machines and the like comprising a long transfer sheet with transverse slightly staggered zigzag folds incorporated

therein at uniform and relatively substantial spaces from one another to arrange the sheet in form of a short rectangular pack, the sheet being coated with transfer material on one side and also being coated with a smooth material on the other side, whereby a first set of the slightly staggered zigzag folds exposes said smooth material to the outside and a second set of said slightly staggered zigzag folds exposes said transfer material to the outside; a holder sheet for the transfer sheet with a holder bottom approximately as wide and long as the folded pack and with a holder top flap hinged to the holder bottom, the folded pack being inserted in the holder sheet with the second set of staggered zigzag folds adjacent the hinge of the top flap; and a seal pad secured to the holder bottom, located below and extending substantially across the first set of folds but not substantially beyond such folds, said pad providing, in engagement with such folds, a layer of substantially non-repeat adhesive material adapted to adhere to said smooth material in a manner releasable by peeling off but unreleasable by forces directed parallel with the transfer sheet.

2. A carbon pack comprising a long carbon sheet with a plurality of transverse slightly staggered folds incorporated therein at uniform and relatively substantial spaces from one another to form the sheet into a zigzag folded pack, said sheet being coated with carbon ink on one side whereby a first set of the slightly staggered folds exposes a surface not so coated to the outside and a second set of slightly staggered folds exposes carbon ink to the outside; a holder sheet comprising a holder bottom slightly wider and longer than the folded pack and with a holder top flap hinged to the holder bottom, the folded pack being inserted in the holder with the second

5 set of staggered folds adjacent the hinge of the top flap; and a plurality of dry seal pads secured to the holder bottom, each seal pad being a narrow strip extending from adjacent the first to adjacent the last fold of the first set of folds and each pad providing in engagement with said folds a layer of substantially non-repeat adhesive material to seal such folds to the holder bottom in a manner releasable only by peeling off.

10 3. A transfer unit for billing machines and the like comprising a long transfer sheet zigzag folded to form a rectangular pack the folds of which are staggered, the sheet being coated with transfer material on at least one side; a holder sheet 15 for the transfer sheet with a holder bottom substantially as wide and long as the folded pack and with a holder top flap hinged to the holder bottom above the folded pack; and at least two seal strips, parallel with one another and transverse to the hinge between the holder bottom and the top flap, extending between the holder bottom and the folded pack, having a substantially non-releasable coating at the undersides of the seal strips, in engagement with the holder 20 bottom, and having a seal coating releasable by peeling off, at the top of the seal strips, in engagement with the folded pack.
